UNITED STATES PATENT OFFICE.

RAMON M. RODRIGUEZ, OF NEW YORK, N. Y.

DESIGN FOR A BOX FOR TALCUM POWDER AND SIMILAR MATERIAL.

Application filed September 1, 1922. Serial No. 3,618. Term of patent 14 years.

To all whom it may concern:

Be it known that I, RAMON M. RODRIGUEZ, a citizen of the United States, and resident of the borough of Manhattan, city, county, and State of New York, have invented a new, original, and ornamental Design for a Box for Talcum Powder and Similar Material, of which the following is a specification.

Reference is to be had to the accompanying drawing which illustrates, in elevation, a box embodying the design.

The design relates to boxes intended more particularly for talcum powders and similar material.

I claim:

The ornamental design for a box for talcum powder and a similar material as shown and described.

RAMON M. RODRIGUEZ.
